UNITED STATES PATENT OFFICE.

WESLEY FIELDS AND DANIEL D. MAYFIELD, OF ROBINSON, ILLINOIS.

IRONING-STAND.

SPECIFICATION forming part of Letters Patent No. 267,857, dated November 21, 1882.

Application filed February 23, 1882. (No model.)

To all whom it may concern:

Be it known that we, WESLEY FIELDS and DANIEL D. MAYFIELD, citizens of the United States, of Robinson, in the county of Crawford and State of Illinois, have invented a new and valuable Improvement in Ironing-Stands; and we do hereby declare that the following is a full, clear, and exact description of the construction and operation of the same, reference 5 being had to the annexed drawings, making a part of this specification, and to the letters and figures of reference marked thereon.

Figure 1 of the drawings is a representation of a vertical sectional view of our improved ironing-stand, and Fig. 2 is a bottom view of the same.

This invention has relation to ironing-stands; and it consists in the novel construction and arrangement of parts, as will be hereinafter 20 fully described, and particularly pointed out in the claims.

In the accompanying drawings, the letter A designates the longer legs of the stand or table, which are connected near their lower ends by 25 the round, step, or cleat, a, and pivoted near their upper ends to the cleat b, which is secured to the end of the board B, between the oblique shoulders c of said board, against which the legs A rest when in an unfolded position, by 30 their upper extensions, d, to which the head-rest or transverse shelf C is pivoted. This head-rest C is provided with arms e e', which are pivoted to the leg-extensions d, and the former of these arms is made with a circular 35 slot, g, through which extends a clamp-screw, h, designed to hold the head in position securely after adjustment. This head or shelf is designed to take two positions, one parallel to the ironing-board and the other at right angles thereto, when the board is placed on end 40 in position to serve as a step-ladder.

D represents the short legs, which are pivoted between the long legs A, and are firmly connected by means of the steps or rounds a' 45 and the slotted end bar, k, which, when the stand is unfolded, is connected to the board B by means of a cleat, l, and button m. When folded within the long legs, and flush therewith,

the short legs are kept in position by means of buttons z, pivoted to the upper and lower 50 portions of said long legs, and so arranged in order to prevent the legs D, to which the three main steps or rounds a' are attached, from moving out of position when the stand is placed on end for use as a step-ladder.

E represents the press-board, having supporting-cleats n underneath, and provided with a clamp-screw, p, which passes through a perforation, q, near the end of the board B, and is secured on the under side thereof by a nut, 60 s. This press-board is designed to be turned laterally in either direction, and can be readily and quickly removed.

F indicates a side leaf, which is hinged at t to the edge of the ironing-board B, and is 65 turned up when a wide board is required. This falling leaf is supported in the raised position by means of a slide or button, the latter being shown in the drawings at v, pivoted in position to be turned within the space between the legs 70 of the stand when the latter are folded up against the board.

Having described this invention, what we claim, and desire to secure by Letters Patent, 75

1. The folding ironing-stand having the board B, the long legs A, short legs D, steps or rounds a a', buttons z, and adjustable head-shelf C, substantially as specified.

2. The combination, with the extensions d 80 of the long legs A, of the adjustable head-shelf C, its arms e e', circular slot g, and clamp-screw h, substantially as specified.

3. A combined ironing-stand and step-ladder having the adjustable head-shelf C, adapted 85 to be secured in position either parallel to or in angular relation to the ironing-board, as specified.

In testimony that we claim the above we have hereunto subscribed our names in the 90 presence of two witnesses.

WESLEY FIELDS.

DANIEL D. MAYFIELD.
